COAL WASHING MACHINE

Gustave Andre Vissac, Blairmore,
Alberta, CanadaApplication March 21, 1934, Serial No. 716,707
In Canada April 27, 1933

4 Claims. (Cl. 209—457)

This invention relates to improvements in coal washers of the type in which the particles of coal are separated from the particles of rock by means of an upwardly flowing column of water, 5 into which both the coal and the rock are introduced and from which they are separately withdrawn, and the objects of the invention are to effect a more economical and accurate separation, to prevent back currents in the column of water, 10 and to create therein the proper still condition which will enable separation to be readily effected by differences in specific gravity. Further objects of the invention are generally to simplify and improve a coal washer and the method of operating the same to effect the best separation without costly sizing and with a minimum consumption of power.

Carrying out the invention, instead of using a single current of water to effect the separation I 20 employ a combined current formed from streams of different velocities, one of which is pulsating, and I employ these streams in apparatus having various improved mechanical arrangements as will be hereinafter more fully set forth and described in the accompanying specifications and drawings.

In the drawings Fig. 1 is a longitudinal section of a coal washer embodying the invention.

Fig. 2 is a plan view.

Fig. 3 is a section on the line 3—3 of Fig. 1.

Fig. 4 is an assembly plan showing several units assembled for use on small coal sizes.

In the drawings like figures of reference indicate corresponding parts in all the figures.

Referring to the drawings, 1 indicates the main water supply valve controlling the inflow of water through the main inlet pipe 2 which opens into the main water supply chamber 3, the latter conveniently having air pet cocks 4 in the wall thereof 35 which may be manually operated to regulate the level of liquid in the chamber 3. 5 indicates a butterfly valve driven at variable speed by suitable means and designed to produce a pulsating current of water as hereinafter described.

6 is an auxiliary supply valve leading from the chamber 3 by which a continuous current of water of regulated amount is supplied.

7 indicates a current deflector pivotally mounted and designed to be adjustably held in any position by which the upward current may be deflected acting in combination with the deflector plate 8 at the bottom of the main surge chamber 8. At the bottom of the surge chamber 8 is connected an auxiliary water supply 10 controlled by 50 an auxiliary water supply valve 11 and having a

sludge valve 12 through which the sludge may from time to time be withdrawn.

On the upper part of the surge chamber 8 an inclined perforated plate 13 is provided leading to the rock discharge 14. The clean coal is adapted to be discharged at the upper end and through the discharge port 15 and over the clean coal grate 16 which is adjustable in position so that its upper level may be changed. Adjacent to this coal grate but below the same is a rock gate 10 17 immediately above the opening 14. The rock passing through the discharge 14 is designed to fall into a rock scraper conveyor 18 of any convenient design, shown schematically in Fig. 4, by which it is conveyed away. The clean coal passes 15 out through a clean coal discharge 19.

The raw coal is designed to be supplied from a bin 20 to one or more feed gates 21 the passage being assisted by flushing water controlled by the flushing feed water valve 22.

The water within the surge chamber 8 is further controlled by an outlet leading from above the conveyor 18 and controlled by a depression butterfly valve 23. The amount of the opening of this valve is designed to be automatically controlled by means of a lever 23a connected by links 24a, 24b, and a pivoted rocker arm 24c to a weight 24 suspended within the chamber 8 and operating as hereinafter described.

Having now described the various parts of the 30 apparatus I will briefly refer to the method of operating the same.

The raw coal is delivered into the bin 20 and is discharged and controlled by a series of gates 21 and thence flushed along a suitable trough into 35 the top of the surge chamber 8 by means of water controlled by the flushing valve 22. By properly regulating this current of water an initial separation of the coal (shown in black) from the rock (shown in white) is effected, the lighter pieces of coal being projected further up in the washing box or surge chamber 8 than the pieces of rock. It is desirable that for greater efficiency the bottom of the trough should be as close as possible 40 to the level of the water in the chamber 8.

While the device is in operation a continuous upward current of water is maintained in the surge chamber 8 whose speed is adjusted by means of the valves 1 and 6. The minimum speed of this stream (VI) should be just below 50 the limit speed of free fall of the lightest pieces of coal in water; in other words, when the water current in the surge chamber 8 attains that speed (VI) the coal pieces are practically still or just start to fall and, naturally, the rock pieces sink. 55

The rotating valve 5 is continually rotated and thus opens and closes a further outlet from the chamber 3 to the chamber 8, thereby periodically increasing the speed of the upward current in 5 the tank 8 to the maximum speed (V2). The regulation of this additional pulsating current which combines with the main current of water may be made by adjusting the main valve 1 and regulating the speed of rotation of the valve 5 to a definite number of revolutions per minute. The maximum speed of the current of water (V2) should be theoretically that which will maintain the rock 10 still and move the coal upward. In this way the raw coal in the surge chamber 8 is submitted to a series of speeds varying between V1 and V2 15 causing the coal to remain still or to move upward and the rock to sink down or to remain still. In other words the coal is gradually jumping up and the rock is gradually sinking down. The coal 20 is finally evacuated with the water by the overflow at 15 whose level is adjusted by gate 16 and the rock falls onto the perforated plate 13 which has a slope just sufficient to allow the rock to slide down gently to the scraper conveyor 18 which 25 moves it out gradually. The sliding gate 17 and the depression water valve 23 allows the necessary adjustment to be made to maintain a protective bed of rock on the perforated plate. The depression butterfly valve 23 also enables a very 30 accurate control to be maintained of the water conditions in the surge chamber 8. The cylinder 24 is selected of proper weight and is designed to rest on the rock bed so that as the rock bed increases the weight will be raised which will adjust the butterfly valve through the chain and pulley connections shown and thereby effect a 35 regulation in the outflow from the chamber 8.

All the water required for the operation is supplied from the pipes 2 and 22, and which should 40 be connected to a centrifugal pump. All of the upward current of water is fed by the pipe 2 and distributed equally over the surface of the plate 13 from the tank 3. The opening of the valve 6 supplying the main current and the valve 5 supplying the pulsating current are conveniently extended across the whole width of the washing tank.

It will be seen that the rotating valve 5 is open 45 on only part of its revolution. When the valve 5 is closed the continuous water pressure (brought in by pipe 2 from the continuous current of the feeding centrifugal pump) is used to compress the air on top of the tank 3; when valve 5 opens this air pressure is used to bring up the speed 50 of the upward current in the surge chamber in the proper manner and to the proper amount. During the operation the air in the tank 3 is compressed by the water pressure only and mostly is not allowed to escape. There is always a continuous upward current of water through the 55 washing bed which positively ensures against back streams and back currents and enables the device to create very still water conditions for the separating of the rock from the coal. These still conditions, realized for light pieces at minimum current and for heavier pieces at maximum current, enable the separation to be effected by differences of acceleration and consequently by differences in specific gravity only independently of 60 their size. The prevention of back currents is desirable as their existence would mean a destruction of the separation accomplished in the upward current since they produce conditions in which light pieces would sink faster than heavy ones. It is possible by the device to effect an 65

efficient separation without previously sizing the particles of coal. The consumption of water is very low and substantially less than in a continuous upward current machine. The moving parts are few including only the valve 5 and the rotary conveyor. The device may therefore be operated with minimum consumption of power. 5

The butterfly valve 5 which controls the passage of water from the chamber 3 to the chamber 8 extends across the full width of the chamber so that, when it is open, a rapid surge of water from the chamber 3 into the chamber 8 takes place, producing an upward current in the chamber 8 which however is decelerated as the head of water in the chamber 3 is reduced and/or the air pressure released. When this butterfly valve or gate 5 is in closed position, which is only during less than half of its rotation, water and air pressure is accumulated in the chamber 3. When the gate 5 opens this accumulated pressure 10 at its maxima, is relieved through the whole width of the machine sharply and quickly. Thereafter the pressure in the tank compartment 3 decreases and upsurge takes the form of a uniformly retarded motion; consequently, the particles are 15 retarded according to their specific gravity alone, particles of lightest specific gravity go upwardly with the greatest acceleration. At the end of this upsurge practically still conditions prevail in the chamber 8, particles are falling with an acceleration 20 according to specific gravity alone. The downstroke then develops. During this downstroke, while the valve 5 is closed the water flows through the valve 6 in a continuous current, which current however is accelerated through the 25 building up of hydrostatic and pneumatic pressure in the chamber 3 so that the continuous current of water flowing upwardly is gradually accelerated, with the result that the relative motion of the particles is an accelerated downward 30 motion. 35

The description as shown in Figures 1 to 3 illustrates the general application of the invention. When it is desired to operate on very small sizes of coal containing a large amount of middlings 40 an arrangement such as shown in Fig. 4 may be provided in which a plurality of units similar to those shown in Figures 1 to 3 are assembled side by side. The water current in this case is parallel to the partition between the air and 45 washing tank. Two washing tanks are provided each one having two air tanks. The first washing tank may eliminate a heavy refuse by a screw conveyor rather than by a scraper conveyor, while the second tank eliminates a middling product. 50 55

The automatic regulation effected by means of the weight 24 may, if desired, be modified by placing the cylinder 24 in the rock chamber 25 above the conveyer, the cylinder in this case being a float, and operates by reason of the fact 60 that an increased bed of rock will give an increased pressure in this chamber. It will be understood that the butterfly valve can be replaced by any equilibrated valve. It will be obvious that the water supplied by the pipes 2 65 and 22 can be supplied from a pump or tank or any water system having the necessary head or pressure.

Although the invention has been described herein with reference to the use of water as the 70 separating medium, it will be understood that any other fluid might be used if available, and the term "water" in the following claims is intended to include any such fluid.

Various modifications may be made in the 75

invention without departing from the spirit thereof or the scope of the claims and, therefore, the exact forms shown are to be taken as illustrative only and not in a limiting sense, and I desire that only such limitations shall be placed thereon as are imposed by the prior art or are specifically set forth in the appended claims.

What I claim as my invention is:

1. The method of separating mixed materials of different specific gravities, which consists in passing such materials to a counter-flow of a continuous current of water, gradually accelerating the current from a minimum to a maximum velocity, suddenly increasing the volume of the current as it reaches maximum velocity and then gradually decelerating it to initial minimum velocity, decreasing the volume of the current to its initial volume, and successively repeating the cycle while passing material to the current.
2. The method of separating mixed materials of different specific gravities, which consists in passing such material downwardly into a continuously up flowing current of water, gradually accelerating the velocity of the current to a peak sufficient to suspend the fall of the heavier material, then suddenly increasing the volume of the current to cause a surge lifting the lighter material above the heavier and at the same time decelerating the current velocity to permit free fall of the heavier material, decreasing the current to its initial volume, and successively repeat-

ing the cycle while passing material into the current.

3. In a system for washing coal or the like, the method of effecting separation of the lighter material from the heavier which consists in feeding a batch of material into a counter current of water flowing at a velocity sufficient to retard all of the lighter material and to permit fall of the heavier material, gradually accelerating the current velocity to a point sufficient to suspend fall of the heavier material, then suddenly increasing the volume of the current to cause a surge lifting the lighter material away from the heavier and immediately thereafter decelerating the current velocity to a point sufficient to permit free fall of the heavier material and decreasing the current to its initial volume.

4. In a jig, a surge chamber having an inclined screen therein, a pressure chamber adjoining said surge chamber, means for supplying water to said pressure chamber against pressure therein, a passageway connecting said chambers below said screen, valve means in said passageway for periodically allowing feed of water under pressure from said pressure chamber in surges to the surge chamber, and valve means also in said passageway adjacent said first-named valve means, said second valve means being adjustable and continuously open to establish a constant flow of water from said pressure chamber upwardly through the screen in said surge chamber.

GUSTAVE ANDRE VISSAC.
